SAMPLER

Filed March 12, 1930

INVENTOR

Robert W. Ellms

Thomas W. Clark

ATTORNEY

UNITED STATES PATENT OFFICE

ROBERT W. ELLMS, OF BALTIMORE, MARYLAND

SAMPLER

Application filed March 12, 1930. Serial No. 435,294.

The invention relates to a sampling device for taking core samples of material from a bulk to determine the characteristics of the bulk.

The device was developed when the need of accurately determining the nature of a river bed was presented. Methods then known allowed for too much slipping of material from different levels into the sampler; the stratification of the material could not be found. With my device the actual, undisturbed, stratification, and nature of the material can be determined. The objects of my invention are to make a sampler that may be driven into the material closed, to a given depth, that may then be opened to receive a sample, at one or more levels, that has means to draw material into the pockets provided in the sampler, that may be closed and removed and the sample removed without danger of admixture with other materials, that has means to prevent serious breakage to the device should hard obstructions be encountered. Other objects and advantages will be apparent as the description of the device proceeds.

In the drawings forming a part hereof, Figure 1 is a front view of the device with the flaps and ports open, partly broken away. Fig. 2 is an enlarged cross section of a pocket, open, showing a flap open. Fig. 3 is a view similar to Fig. 2 with the port and flap closed. Fig. 4 is a cross section, showing the slipping fin. Fig. 5 is a perspective view of a cup. Fig. 6 is an alternative point. Fig. 7 is another alternative point.

Similar numerals refer to similar parts throughout the several views.

Outer tube 1 has therein a plurality of openings 2 extending longitudinally of the tube and not quite half way around it. An inner tube 3 has similar openings 4 in its walls. These several openings in both tubes are preferably placed angularly from each other around the tubes to give the tubes greater strength. Between the openings in the inner tube 3 wooden blocks 5 are placed to prevent material from passing from one opening to another, so that a pocket may be formed in the tube. Within these pockets,

cups 6, are removably placed, having a hole 7, fitting over a pin 8, in the lower block 5 of the pocket, to prevent rotation or falling out. Clip 9, on each cup, is snapped under a shoulder of inner tube 3, to hold the cup securely in place.

Cutter flaps 10 are hinged axially to one side of the openings in outer tube 1, which serve to dig into the material in filling and to direct the material into the pockets. These flaps have stops 11 at their backs to limit their opening angle, preferably several flaps are at each pocket, so that should one be injured, the others will function. A penetrating point 12 is at the end of the outer tube, fastened to the tube by a wooden section 13, which will break should an obstruction be met, and which will, therefore, prevent injury to the tubular structures. A screw pulling point 14 may be used instead of the conical point 12, if desired, or a knife point 15 may be used.

At the upper end of the outer tube 1, a circumferential slot 16 extends part way around the tube, and a stud bolt 17 on inner tube 3 works in this slot. Above this bolt 17 on the inner tube, the inner tube may be extended by adding sections of tubing and bolting them together to prevent relative rotation, so that the desired depth under water may be reached with the sampler.

A fin 18 is bolted to the outer tube, and held from longitudinal movement by fixed collars 19. The fin is so bolted as to rotate fairly tightly on the outer tube.

In operation, the inner tube is turned so that the openings are closed, and the cutter flaps hug the outer tube, and the device is then driven into the material. The inner tube is then turned and this turning will first open the openings or ports, then bolt 17 will reach the end of its slot and the outer tube will be rotated; this will cause the opening of the cutter flaps and they, in turn, will cause material to enter the ports. When a sample has entered the ports, the inner tube is reversely rotated, which will first close the ports, then cause the cutter flaps to draw in against the outer tube, then the device is

withdrawn, raised, opened, and each cup emptied into a marked receptacle.

The fin 18 allows the ports to be opened and closed should the device be used in very loose material that might not hold the outer tube from rotating while the inner tube is rotated to open and close the ports. After the ports are opened, the fin will slip on the outer tube while samples are being taken.

Although the device has been described as a sampler for the materials of the bed of a river, or the like, obviously it may be used, with many of its advantages, to sample other materials in other conditions and the form hereinbefore described is merely a preferred embodiment, many changes may be made without departing from the spirit or scope of the invention.

I claim:

1. A sampling device comprising a tube having an opening in the side thereof, cutter flaps pivoted to one side of said opening, and extending substantially the length thereof, means to limit the opening angle of said flaps, said flaps, when closed, being adapted to partially cover said opening.

2. A sampling device comprising an outer tube having an opening in the side thereof, an inner tube within said outer tube having a corresponding opening in the side thereof, a cutter flap on said outer tube adjacent said opening to draw material into said opening, means to rotate said device to draw in material and to rotate said tubes relatively to each other to close the opening in the outer tube with the inner tube.

3. A sampling device comprising an outer tube having an opening in the side thereof, an inner tube within said outer tube having a corresponding opening in the side thereof, a cutter flap pivoted on the outer tube to one side of said opening, means to limit the opening angle of said cutter flap, and means to rotate said device to draw in material and to rotate said tubes relatively to each other to close the opening in the outer tube with the inner tube.

4. A sampling device comprising an outer tube having an opening in the side thereof, an inner tube within said outer tube having a corresponding opening in the side thereof, a removable cup in said inner tube adapted to receive material entering through said openings and to be removed through said openings, and means to rotate said tubes relatively to each other to close the opening in the outer tube with the inner tube.

5. A sampling device comprising an outer tube having an opening in the side thereof, an inner tube within said outer tube having a corresponding opening in the side thereof, a slipping fin on said outer tube, means to rotate said inner tube in one direction to open said openings and to cause material to be caught in said openings, and in the reverse

direction to close the opening in the outer tube with the inner tube, said fin being adapted to slip on said outer tube during the filling operation, and to substantially prevent rotation of said outer tube during the opening and closing operation of said openings.

6. A sampling device comprising an outer tube having an opening in the side thereof, an inner tube within said outer tube having a corresponding opening in the side thereof, means to rotate said tubes relatively to each other to close the opening in the outer tube with the inner tube, a penetrating cap at the end of said outer tube, said cap being attached to said outer tube by a breakable section.

7. A sampling device comprising an outer tube having a plurality of longitudinally spaced openings in the side thereof, an inner tube within said outer tube having a plurality of corresponding openings in the side thereof, removable cups in said inner tube adapted to receive material entering through said openings, and means to rotate said tubes relatively to each other to close the openings in the outer tube with the inner tube.
